(57) **CLAIM**

The ornamental design for a pedal exerciser, as shown and described.

DESCRIPTION

FIG. 1 is a perspective view of a pedal exerciser showing the new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof;

FIG. 8 is an enlarged perspective view of a portion in FIG. 1;

FIG. 9 is an enlarged perspective view of a portion in FIG. 2; and,

FIG. 10 is an enlarged perspective view of a portion in FIG. 6.

The broken lines shown in the figures are for the purpose of illustrating portions of the pedal exerciser and form no part of the claimed design.
